CONVERSION OF HYDROCARBON OILS

Edwin F. Nelson, Chicago, Ill., assignor, by mesne assignments, to Universal Oil Products Company, Chicago, Ill., a corporation of Delaware

Application November 10, 1930, Serial No. 494,550
Renewed February 12, 1935

3 Claims. (Cl. 196—66)

This invention relates to the conversion of hydrocarbon materials and particularly refers to the simultaneous conversion of hydrocarbon oil and natural gas.

5 The present invention embodies the concepts of an improved process and apparatus wherein natural gas or other hydrocarbon gas of similar nature is subjected to conversion at an elevated temperature, preferably under super-atmospheric 10 pressure, and the products of such conversion are utilized to assist the conversion of relatively heavy hydrocarbon oil into lighter and more valuable products.

In a more specific embodiment of the invention 15 a hydrocarbon gas, such as natural gas or any hydrocarbon material of a similar nature in a gaseous state, is subjected to elevated temperatures in a heating element, preferably maintained under super-atmospheric pressure, to effect conversion of the gas preferably into substantial 20 quantities of aromatic compounds and hydrogen, the effluent from the heating element being rich in aromatics and hydrogen. Simultaneously hydrocarbon oil is subjected to conversion conditions in a separate heating element, the materials resulting from conversion of the gas being introduced into the stream of hydrocarbon oil entering said separate heating element or into the stream of heated materials emerging from 25 said separate heating element or partially into both streams; the combined heated materials are introduced into an enlarged reaction zone where separation of vapors and unvaporized residual material is effected, vapors from said enlarged reaction zone being subjected to fractionation, the relatively heavy insufficiently converted portion of the vapors being condensed in the fractionating zone and returned to reconversion, and the relatively light portion of the fractionated vapors of the desired composition being subjected to condensation and cooling and the products collected.

The attached diagrammatic drawing illustrates 45 one form of apparatus in which the process of the present invention may be practiced and the following description of the drawing embraces also a description of the operation of the process as it may be practiced in the apparatus shown.

Raw oil charging stock for the process introduced through line 1 and valve 2 to pump 3 may 50 be fed through line 4 and valve 5 into fractionator 6 where it is preheated by contact with vapors in this zone assisting in their fractionation and passing together with the heavier condensed 55 portion of the vapors through line 7 and valve

8 to pump 9. A portion or all of the raw oil charging stock may, if desired, be diverted from line 4 and from fractionator 6 and is fed through line 10 controlled by valve 11 into line 1 where it combines with the reflux condensate from 5 fractionator 6, passing to pump 9. The combined materials are fed by pump 9 through line 12 and valve 13 into heating element 14.

Heating element 14 is located in any suitable form of furnace 15 and the materials passing 10 therethrough are heated to the desired conversion temperature under any desired pressure conditions and pass therefrom through line 16 and valve 17 into reaction chamber 18.

Hydrocarbon gas, such as natural gas or any 15 other hydrocarbon material of similar nature in a gaseous state, is supplied through line 19 and valve 20 to pump 21, is fed through line 22 and valve 23 into heating element 24, which is located in any suitable form of furnace 25 and in which 20 the gas is heated to the desired conversion temperature under any desired pressure conditions. Materials leaving heating element 24 may pass through line 26 and valve 27 or through line 25 52, valve 53, pump 54, valve 55 and line 56 and may be passed through line 28 and valve 29 into line 12 combining therein with the stream of oil passing to heating element 14. Likewise a portion or all of the materials from heating element 24 may pass from line 27 or line 56, as 30 the case may be, through line 30 and valve 31 into line 16 combining therein with the stream of heated materials from heating element 14. A portion of the material discharged from heating element 24 may be recirculated thereto for re- 35 conversion by diverting it from line 28 through line 32 controlled by valve 33 and through line 19 to pump 21.

The combined materials from heating elements 14 and 24 pass through line 16 and valve 17 to 40 reaction chamber 18 where separation of vapors and unvaporized material is permitted. Unvaporized residual liquid may be withdrawn from chamber 18 through line 34 controlled by valve 35 to storage or to further treatment as desired. 45

Vapors from chamber 18 pass through line 36 and valve 37 to fractionator 6 where they are subjected to fractionation, their relatively heavy insufficiently converted portion being condensed therein and returning to reconversion, as 50 already described, while the relatively light fractionated vapors of the desired composition pass through line 38 and valve 39, are subjected to condensation and cooling in condenser 40, condensed and uncondensed products from which 55

pass through line 41 and valve 42 to be collected in receiver 43. Condensed distillate may be withdrawn from receiver 43 through line 44 and valve 45. Uncondensed gaseous products may be released through line 46 controlled by valve 47. A portion of the condensed distillate from receiver 43 may be withdrawn through line 48 and valve 49 and recirculated by means of pump 50 through line 51 and valve 57 to fractionator 6 to assist fractionation of the vapors in this zone.

Substantially equalized pressure may be employed throughout the system or differential pressures may be utilized between the various elements. Conversion temperatures employed may range from 750 to 1600° F., more or less. Preferably the gas is subjected to more severe conversion conditions than those employed in the heating element utilized for the conversion of the oil.

As a specific example of operating conditions which may be employed in an apparatus such as illustrated and the improved results which may be obtained from such operation, the raw oil charging stock is a fuel oil of about 22° A. P. I. gravity and is subjected in heating element 14, together with approximately 6 percent by weight, based on the raw oil charging stock, of material from heating element 24, to a conversion temperature of approximately 880° F. under a super-atmospheric pressure of about 350 pounds per square inch. About 20 percent by weight of natural gas, based upon the raw oil charging stock, is subjected in heating element 24 to a conversion temperature of approximately 1200° F. under a super-atmospheric pressure of about 1500 pounds per square inch.

Products from the conversion of the gas introduced, in part, to the inlet of heating element 14, as already described, and in part to the outlet from heating element 14 pass together with the converted oil from heating element 14 to reaction chamber 18 wherein a pressure of about 350 pounds per square inch is maintained. This pressure is substantially equalized in the succeeding portions of the system, namely, the fractionating, condensing and collecting equipment. A yield of about 65 percent of motor fuel having anti-knock characteristics equivalent to a blend of approximately 60 percent benzol and 40 percent straight-run Pennsylvania gasoline may be obtained. In addition about 20 percent of residual oil substantially free from suspended carbonaceous material and suitable for sale as premium fuel and about 10 percent of pressure distillate bottoms suitable as cracking stock for the production of high anti-knock motor fuel

may be obtained. The above yields are based on the volume of raw oil charged to the system. The uncondensable gas produced by the system is approximately equivalent to the natural gas fed to the system but is higher in calorific value and richer in hydrogen content than the natural gas and may be utilized in hydrogenating processes, may be blended with gas of lower calorific value to improve its quality, or may be otherwise utilized as desired.

10

I claim:—

1. A process for converting hydrocarbon oils comprising passing charging oil into a primary heating zone wherein it is subjected to cracking conditions of temperature and pressure, introducing gaseous hydrocarbons into a second heating zone and subjecting them to temperature and pressure conditions adequate to produce aromatic hydrocarbons and hydrogen, withdrawing the conversion products from the second heating zone and commingling at least a portion thereof with the charging oil entering the primary heating zone, another portion of the conversion products being recycled to the second heating zone.

15

2. A process for converting hydrocarbon oils comprising passing charging oil into a primary heating zone wherein it is subjected to cracking conditions of temperature and pressure, introducing gaseous hydrocarbons into a second heating zone and subjecting them to temperature and pressure conditions adequate to produce aromatic hydrocarbons and hydrogen, withdrawing the conversion products from the second heating zone and commingling at least a portion thereof with the hot oil leaving the primary heating zone, another portion of the conversion products being recycled through the second heating zone.

25

3. A process for converting hydrocarbon oils comprising passing charging oil into a primary heating zone in which it is subjected to cracking conditions of temperature and pressure, introducing gaseous hydrocarbons into a second heating zone and subjecting them to temperature and pressure conditions adequate to produce aromatic hydrocarbons and hydrogen, withdrawing the conversion products from the second heating zone, commingling one portion thereof with the charging oil entering the primary heating zone and commingling another portion thereof with the hot oil leaving the primary heating zone, a further portion being recycled through the second heating zone.
